John A. Heath,

UNITED STATES PATENT OFFICE.

JOHN A. HEATH, OF LOYAL, WISCONSIN.

BILLIARD-CUE.

SPECIFICATION forming part of Letters Patent No. 668,182, dated February 19, 1901.

Application filed June 4, 1900. Serial No. 19,054. (No model.)

To all whom it may concern:

Be it known that I, JOHN A. HEATH, a citizen of the United States, residing at Loyal, in the county of Clark and State of Wisconsin, have invented new and useful Improvements 5 in Billiard-Cues, of which the following is a specification.

My invention relates to improvements in billiard-cues; and the object is to provide 10 means whereby the top of the cue may be readily and conveniently secured in position and as readily and conveniently detached whenever desired or required; and the invention consists in the novel construction, arrangement, oraggregation of parts, as will be hereinafter more fully described and the novelty thereof particularly pointed out in the claims.

I have fully and clearly illustrated my improvements in the accompanying drawings, 20 wherein—

Figure 1 is an elevation of a billiard-cue having my improved tip appliances connected therewith. Fig. 2 is a view in elevation, partly in vertical central section, through the 25 parts of the tip connection, showing them assembled and secured in proper position.

Referring to the drawings, 1 designates the cue of a common and approved construction, on the end of which is fitted and secured by 30 any proper means a socket-ferrule 2 of such length as to properly meet the requirements of a solid and steady connection to the cue. Centrally from the bottom or bridge of the socket of the ferrule is projected a vertical 35 screw-threaded stem 3 of such length and strength as may be necessary to hold the combined parts strongly in assembled position.

4 designates a washer having a central aperture which loosely fits over the threaded stem 3 and seats upon the alining surface of the outer face of the socket-ferrule, as indicated in Fig. 2 of the drawings.

The upper portion of the washer 4 is cored 45 out, so that the bore thereof is larger than the central aperture of the lower portion through which the stem 3 projects, thus forming a vertical annular flange 5, as indicated in the drawings in Fig. 2. The washer 4 has its upper surface preferably roughened or corrugated in order to more firmly and securely

grip and hold the tip in position. The screw-threaded stem 3 protrudes a sufficient distance beyond the face of the washer 6 to impinge against the inner face of the tip and 55 give it a greater tension.

6 designates a clamping-nut having a central screw-threaded aperture 7 and a depending circular extension 8, through which the screw-threads are extended, whereby the 60 clamping-nut may be arranged upon the threaded stem of the socket-ferrule and then turned down upon the said stem, as may be desired. The clamping-nut is also formed with an annular depending flange 9, reaching down over the vertical annular flange of the washer, the interior diameter of the depending flange being somewhat larger than the diameter of the vertical flange of the washer 4 in order that the skirt or flange of 65 the tip may be turned under and then upward and inclosed in the space between the depending flange of the clamping-nut and the vertical annular flange of the washer, so that the turned-up edge of the skirt may lie 70 over the top edge of the vertical flange of the washer and be clamped thereon by the clamping-nut.

The outer surface of the vertical flange 5 of the washer 4 is circumferentially reduced to 80 receive the skirt of the tip, and the diameter of the nut 6 is less than that of the washer 4, so that the skirt of the tip will be flush with the periphery of said washer. In order that a firmer frictional engagement may be 85 secured and the tip more firmly held in position, I preferably form the periphery of the clamping-nut with corrugations adapted to engage the skirts of the tip.

10 designates the tip, (made, preferably, of 90 leather or of a composition of web fabric and rubber,) from which depends an annular skirt 11, adapted to fit snugly over and inclose the clamping-nut and have the lower edge portions of the skirt turned up within the clamping-space between the washer and the clamping-nut, as is clearly indicated in Fig. 2 of the drawings. In order that the skirt may set closely and firmly about the circumferential face of the clamping-nut and also to 95 permit its edges to be turned into the clamping-space between the nut and the washer,

the skirt may be slitted vertically, being careful that the slits do not extend into the body of the tip.

By the construction above described the tip may be readily and conveniently removed when damaged and replaced by a new one with equal convenience. To apply or secure a new tip in position, the washer is placed in position on the stem of the socket-ferrule and the tip is arranged in position on the clamping-nut, with its skirts turned upward, and then the nut, with the tip thereon, is screwed down on the stem and is held secure in position.

15 I claim—

1. A billiard-cue tip comprising a ferrule fitting the end of the case, and having a threaded stem projecting therefrom; a washer fitting over said stem; a clamping-nut on said stem; and a tip proper having a depending skirt clamped between the washer and nut.

2. A billiard-cue tip comprising a ferrule fitting the end of the cue, and having a threaded stem projecting therefrom; a washer fitting loosely over said stem; a clamping-nut adjustable on said stem, and having a depending annular flange; and a tip proper having a depending skirt adapted to be clamped between the washer and nut, and turned up under the flange of the nut.

3. A billiard-cue tip comprising a ferrule having a closed end and a threaded stem thereon; a washer loosely seated on the stem of the ferrule and formed with a vertical annu-

lar flange; the interior of which forms a seat; a clamping-nut having a central threaded aperture to engage the stem of the ferrule and a depending central portion to fit within the seat of the washer, and a tip on the clamping-nut formed with a depending skirt, the lower edge of which is adapted to be turned inward and clamped between the meeting surfaces of the washer and clamping-nut to hold the tip in position.

4. A billiard-cue tip herein described, comprising a socket-ferrule having a closed end and a threaded stem projecting therefrom; a washer loosely seated on the stem of the ferrule, and formed with a vertical annular flange, the interior of which forms a seat; a clamping-seat having a central, threaded aperture to engage the stem of the ferrule; and a depending central portion to fit within the seat of the washer and a depending annular flange extending down over the washer, and a tip on the clamping-nut formed with a depending skirt, the lower edge of which is adapted to be turned up between the depending flange of the nut, and the washer to be clamped between the meeting surfaces of said parts.

In testimony whereof I affix my signature in presence of two witnesses.

JOHN A. HEATH.
